LID REMOVING MEANS FOR CANS

Daniel F. Whitcomb, Los Angeles, Calif., assignor
of one-half to Charles E. Bireley, Los Angeles,
Calif.

Application September 18, 1933, Serial No. 689,855

1 Claim. (Cl. 220—49)

This invention relates to improvements in can opening devices and more particularly to a means for effecting the removal of the closure cap or lip therefrom.

One of the objects of the present invention is to provide a simple, efficient and inexpensive lid removing means for a can or other food container or other container, whereby the can may be manually opened in the minimum length of time and without causing traumatic injury to the operator.

Another object of this invention is to provide a conventional can with self-contained means for enabling a person to quickly remove the top or bottom thereof without the use of extraneous means such as a tool, and without employing even a key.

A further object of this invention is to provide a can with a removable top so designed and shaped that the top may be lifted out of contact from the can and become separated therefrom without loss of time.

A still further object of this invention is to provide a wire so anchored and seated between the lid to be removed and the adjacent parts of the can as to readily be dislodged manually so as to be separated from the can to permit the lid to be readily and uniformly removed from the can to open the latter.

Another important object of this invention is to secure the lid upon the opening of a can so as to close the same in such a manner that the lid may be quickly and effectively pried loose by the simple act of disengaging a wire that binds the lid frictionally in anchored relation in the can.

A still further object of the present invention is to provide a can with an annular top or bottom portion and having an opening designed to be closed by means of a lid. The lid and adjacent section of the can is provided with an annular bead, both beads curving laterally of the seam of the lid and can in opposing directions in such a manner as to provide an annular socket which has a slit opening thereout at the top. A wire is lodged in this socket so that its major diameter is anchored and seated in the socket and its minor diameter projects out of the slit where a terminal on the wire extends. By means of the press fit between both beads of can and of the lid, the wire is pressed into position so that when the operator, desiring to open the can by removing the lid, will grasp hold of the terminal and by exerting a uniform pull upon the wire to lift it out of the socket he will, due to the

wedging action exerted by the wire, readily lift the lid out of the opening of the can, at the same time.

With the above and other objects in view my invention consists in the combination, arrangement and details of construction disclosed in the drawing and specification, in which similar reference characters designate similar parts in the several views of the drawing.

In the drawing,
Figure 1 is a vertical sectional elevation of my invention,

Figure 2 is a top plan view thereof,
Figure 3 is a fragmental detail side view of a can showing the outer bead of the can,

Figure 4 is a cross-sectional view of a can showing the lid wire-bound thereupon to close the opening thereof, and

Figure 5 is a fragmental sectional cross view showing the lid unseated from the fixed bead on the can and from the wire.

In the drawing, which is merely illustrative of my invention 10 generally designates any can, container or vessel made from any desirable material such as metal, paper, cardboard or other material desired. The inside or interior of the can is designated 11, the bottom is designated 12, the bottom bead of annular formation upon the can being designated 13 in which the bottom is clinched securely to close this end of the can or container. The annular flange 14 of the bottom 12 is the part that extends into the bead 13 before both parts are pressed tightly together in the conventional manner.

The can also has, at its opposite end, another annular bead designated 15 in which the flange 17 of an annular member or top portion 17 is contained before this flange and this bead are clinched together operatively. This annular member provides in effect an internal flange upon the interior 11 of the can extending at right angles to the axis of the cap.

The lid 18 is in the form of a disk of metal preferably or of any other suitable material. This disk is made of a size and diameter sufficient to make it snugly fit the opening A provided in the can by the annular flange or top portion 16. The outer circumferential edge of the disk is designed, when the lid accurately fits the mentioned opening, to fit the outer circumferential edge of the flange 16. I provide the outer circumferential edge of the flange 16 with a fixed annular bight M which continues around and back over the marginal portion of the flange and assumes the shape of an annular bead which is concave and

arcuate in cross-section, the bight M making an acute angle with the base portion of the lid 18. In the same manner I form an oppositely extending and similar annular bight N upon the base portion of the lid 18, making an acute angle therewith and continue the bight back upon the marginal portion of the lid so as to assume the shape of an annular bead also formed concave and arcuate in cross-section.

10 The fixed annular bead upon the flange 16 is designated 19, while the bead on the lid is designated 20. From Figure 4 it will readily be seen that both annular beads 19 and 20 come together within touching distance at the points where both bights M and N abut, so that the beads together form an annular socket or groove, semi-circular and dished out in cross-section, the arrangement of both beads also being such as to cause the socket to have a diameter slightly less than 360 degrees, so that thereby the top of the socket forms a slit or provides an annular open portion. The meeting edges of both bights M and N of flange and lid are designated 21. At this time the wire intended to bind the lid upon the flange will be inserted into the fixed annular bead 19 of the flange.

15 The wire 25 is shaped into a coil, and this coil is anchored and seated upon the bead 19, so that one half of the diameter of the wire engages this bead 19, and the other half will be seated into the bead 20 of the lid when the lid is mounted so that its side portion engages the wire, and so that its bight N is in line with the bight M of the flange and the base portion of the lid is in line with the flange 16.

20 This having been done the beads 19 and 20 will be crimped and pinched tightly together against the opposing diametrical sides of the wire 25, and as this is done the wire will be pressed downwardly so as to bridge the meeting edges 21 of flange and lid where the bights M and N are found, so that the circumferential edge or top edge 23 of the bead 20 engages above the half section of the wire, to securely anchor the wire into the socket formed by both beads. Before the wire is thus anchored between the beads I take a rubber cement or gum in a semi-liquid condition and while hot I pour the same between the meeting edges 21, and coat the inner faces of the beads 19 and 20 a slight distance, to provide the sealing material or lining 22. The wire has one end of its split coil cemented or effectively soldered to the lid as at 26, while the other end is extended so as to project out of the socket and is made into a ring or integral hand hold 27. The interior dished out portion of the lid is designated 24.

25 From the foregoing it will readily be seen that with all the parts properly mounted relatively to each other that when the two beads 19 and 20 are pressed accurately together the lid and flange

will be in alignment and the opening of the can closed, and that a fluid tight seal and connection will exist between the flange, and lid excluding air from the interior of the can.

20 In operation the user takes hold of the hand hold or pull ring 27 and begins to raise or lift the same in an effort to circumferentially pry open the wire, and at the same time to loosen and lift the lid out of this opening. Since the greater diameter of the wire is lodged and tightly anchored in the annular socket, and the minor diameter thereof projects outside of the socket, when the pull ring is lifted, it serves to raise the wire out of the socket progressively, and as the wider diameter of the transverse axial portion of the wire is pulled out it wedges against the bead 20 of the lid, lifting the lid as it does so, and in this manner since one end of the wire is soldered to the lid, when the wire is completely separated from between the beads 19 and 20 the lid is completely lifted out of engagement with the can leaving the can opening uncovered, the cement lining being ruptured in the course of separation of the lid from the can. I do not limit myself to the precise details of construction save in and by the claim.

25 What I desire to claim and secure by Letters Patent is:—

30 A tin can having a marginal hook-shaped bead at its top with an annular channel flanking the inner circumference of the can, a horizontally disposed annular tin member extending radially of the can with its outer circumferential edge bent upwardly so as to project into said annular channel in clinched relationship, a cap having a 35 flange formed concavo-convex in cross-section with its concave face outermost, said annular member having an upraised integral flange also formed concavo-convex in cross-section with its concave face at its inner side, the cap flange 40 forming a clinched and annular bead with the base of the can while the member flange also forms a clinched bead with said member, said member providing an opening in which said cap is seated with its base disposed in horizontal 45 alignment with the member so that both clinched beads of both flanges confront each other with a narrow slit intervening, both annular flanges and the clinched beads thereof defining an annular channel dish-shaped in cross-section and representing the major part of the diameter of a circle, a wire of circular cross-section having its major 50 cord seated frictionally with a snap fit into said channel annularly thereof, a cementitious lining adhering to the under face of said wire and filling 55 the slit between the clinched beads, and a pull extension on the wire which when pulled with an upward force will cause the diametrical part of the wire to unseat the cap liftingly.

60 DANIEL F. WHITCOMB.
